UNITED STATES PATENT OFFICE.

LEE WARD, OF YANCEY, TEXAS.

DESIGN FOR AN ANTIRATTLER FOR END-GATES OF WAGONS.

SPECIFICATION forming part of Design No. 35,176, dated October 8, 1901.

Application filed June 18, 1901. Serial No. 65,071. Term of patent 7 years.

To all whom it may concern:

Be it known that I, LEE WARD, a citizen of the United States, residing at Yancey, in the county of Medina and State of Texas, have 5 invented and produced a new and original Design for Antirattlers for End - Gates of Wagons; and I do hereby declare the following to be a full, clear, and exact description of the same, reference being had to the accompanying drawings, forming a part thereof.

My invention relates to antirattlers designed for the end-gates of wagons; and it consists in the new and original design illustrated in the drawings.

15 In the accompanying drawings, forming a part of this specification, Figure 1 is a front elevation of the antirattler, and Fig. 2 is a side elevation of the same looking in the direction of the arrow shown in Fig. 1.

20 The essential feature of my design consists of a helical-shaped body portion, terminating at its upper end in a perforated lug shaped to correspond or register with the top side of an end-gate of a wagon, while the lower end 25 of said body portion terminates in a perforated lug having its lower end bent to form a purchase or handle.

Referring more particularly to the drawings, A denotes the body portion of the antirattler, which consists of a coiled spring. 30

B denotes a lug formed integral with and projecting above the spring, bent at an angle, as shown in Fig. 1, and having at its free end a bolt-hole b, as shown in Fig. 2.

C denotes a lug formed integral with and 35 projecting below the spring-provided perforations c c c, as shown in Fig. 2, and having its lower end c' bent at an angle, as shown in Fig. 1, which serves as a purchase for bearing down on the spring when the antirattler 40 is placed in position.

Having shown and described my invention, what I claim as new, and desire to secure by Letters Patent, is—

The design for an antirattler for the end- 45 gates of wagons substantially as shown and described.

In testimony whereof I affix my signature in presence of two witnesses.

LEE WARD.
